UNITED STATES PATENT OFFICE

HANS P. JESSEN, OF OMAHA, NEBRASKA

ADJUSTABLE SHORE

Application filed November 5, 1927. Serial No. 231,295.

This invention relates to adjustable shores and has particular reference to a means for supporting forms used in casting concrete floors during the construction of buildings.

5 An object of the invention is to provide a means for supporting the forms which is not only adjustable in altitude but is also adjustable transversely and longitudinally.

A further object of the invention is to economize labor during the erection of such form supporting means.

A still further object of the invention is to provide devices which may be taken apart for storing or nesting in compact form for transportation or storage when not in use.

15 A particular object of the invention is to provide a means whereby brace-strips may be attached to the shores for lateral horizontal bracing and spacing and such further objects 20 and advantages as appear from the following detailed description in which:

Fig. 1 is a perspective view of a portion of a concrete form supported by a plurality of the new devices.

25 Fig. 2 is a perspective view of the adjustable shore.

Fig. 3 is a perspective view of a removable joist supporting member.

30 Fig. 4 is a plan view of a detachable foot member employed and Fig. 5 is a perspective view of an adjustable slip-ring or strip-supporting device.

Referring now to the drawing for a more particular description in which like numerals of reference refer to like or corresponding parts throughout the several views, the numeral 10 indicates planks which are placed upon the ground or other support for the purpose of providing a level solid foundation 35 for the reception thereon of the apparatus later described. It will be understood that any suitable number of planks 10 may be used.

40 Referring particularly to Fig. 2, the new device consists of wedge shaped blocks formed preferably of wood having bevelled faces such as is shown at 11. The function of the wood shaped members 11 is to secure fine adjustments after making approximate adjustments of the shores by means later described.

50 Each shore is provided with a foot-plate 12

which is best illustrated in Fig. 4. Each foot-plate is preferably formed by bending upwardly the corners 13 of a rectangular blank of sheet iron 14. The flat bottom of each foot-plate is provided with a plurality of holes 15 for the reception of nails for purposes later described. The upturned ears 13 of each foot-plate are provided with horizontal bolt holes 16 for the reception therethrough of a bolt 17. The function of the bolt 17 is to provide a means for securing to the foot-plate, the lowermost tubular section 18 of the shore which is provided with apertures near its base for the reception of the bolt 17.

55 Indicated at 19 is a second tubular section which is adapted to telescope into and have sliding movements within the lowermost or larger tubular section 18. The section 18 is provided with a plurality of apertures 20 for the selective reception therethrough of a bolt 21. By the above described means it will be obvious that the bolt 21, being passed through selected apertures 20 of the section 18, will provide a means whereby the vertical altitude of the second tubular section may be determined and governed, since the bottom edge of the section 19 will rest upon said bolt and prevent downward travel of the section 19.

60 It will be obvious that any desired number of tubular sections may be provided each telescoping one within the other, but for convenience of illustration, but two are shown, since two tubular sections to each shore will provide for all conventional heights.

65 The uppermost tubular section, which in the present instance, is indicated at 19, is adapted to receive various devices now to be described.

70 As shown in Fig. 2, a casting or head-plate 22, which is preferably provided with a plane rectangular upper surface, is adapted to be maintained in a vertical position by means of the reception of its cylindrical stem 23 within the tubular section 19, said stem 23 being free to have sliding movements within the tubular section 19. 24 indicates re-enforcing webs adapted to provide support for the head-plate 22. Preferably, the head-plate 22, web 24 and stem 23 are formed integral of cast steel or other suitable material.

As best shown in Fig. 3, a joist supporting member 25, which is provided with a shaft 26, and a prong 27, may be selectively interchanged with the member 22.

5 As shown in Fig. 1, the head-plates 22 are adapted to support the beam box 28 of the forms while the joists are supported by means of the member 25.

A slip-ring 29, as best shown in Fig. 5, 10 is adapted to be adjustably secured to and encircle the lower tubular section 18. The location of the slip-ring upon the section 18 may be governed by means of a set screw 30 which when rotated by means of a wrench, 15 will lock the slip-ring 29 in a selected position upon the tubular section 18. The slip-ring 29 is provided with a pair of prongs 31, these being disposed in planes approximately 90 degrees from each other. They project 20 in directions opposed to each other, one prong being turned upwardly and its mate downwardly for purposes later described. It will be understood that any required number of shores may be used for supporting a 25 form, the exact number being governed by the weight of the concrete slab while it is in porous condition.

In operation the planks 10 heretofore mentioned are placed upon the foundation and 30 spaced apart at regular intervals and predetermined distances. The adjustable shores are now placed upon the planks 10 with the thinner edge of the wedge blocks 11 under the foot-plates 12 of each shore. The shores 35 are now spaced apart and placed vertically by means of a lateral brace-strip consisting preferably of a piece of common 1 x 6 indicated at 32. It will be noted that the 1 x 6 is placed in under the downturned prong 31 40 of the slip-ring and is secured to said slip-ring by means of nails. The downturned prong 31 is provided with two nail holes 33 for the reception of the nails 34 shown in Fig. 1. It will be understood that before 45 nailing the 1 x 6 to the downturned prong 31, that the slip-rings are secured to the tubular sections by means of the set screws 30 so that said set screws will be equidistant from the bottom of each shore.

50 By the above described means it will be noted that the shores may be spaced apart and readily locked together at a minimum of expense, since the nails 31 are but temporarily driven into the 1 x 6 brace-strips.

55 Several rows of the shores are erected in the above described manner after which they are locked together transversely by means of 1 x 6 brace-strips 35 which member with the upturned prongs 31 of each slip-ring are 60 secured by nails 36.

It will be noted that preferably each fifth shore is provided with a head-plate 22 at its upper end. The shores containing the head-plates are now moved upwardly to their approximate altitude and the bolts 21 hereto-

fore mentioned, are placed in selected bolt holes 20 for retaining said selected position. Preferably, short pieces of wood such as the blocks 37 are now placed upon the upper surface of each head-plate 22 and the beam boxes 28 are placed thereon. The transverse ship-lap flooring 38 is now secured to the upper edges of each beam box side rail 39. 70

The shores intermediate the shores which are provided with head-plates are now raised upwardly until they substantially butt against the underneath side of the ship-lap flooring 38. The intermediate shores are provided with joist retaining heads such as shown in Fig. 3. Said heads are moved upwardly 75 and retained by means of bolts 21 in the same manner as heretofore described. The heads 25 are adapted to butt against the underneath side of the ship-lap flooring 38. At this time the joist 41 may be placed under 80 the ship-lap and secured to the heads 25 by means of the nails 41' which are passed through the nail holes 42 of the heads 25. If preferred, the joist 41 may be secured to the heads 25 before the heads 25 are raised. 85

After assembling the form and its supports as above described, the operators now 90 secure a leveling adjustment by means of the wedge blocks 11 which are driven one toward the other.

It will be understood that the wedge blocks 11 operate in pairs. Each wedge block 11 is driven towards its mate a sufficient distance to cause the upper end of the shore and the ship-lapping 38 to gain an absolutely level 95 surface which is usually ascertained by means of a spirit level and straight edge in the hands of a mechanic. After securing such adjustment, nails 43 are driven through the nail holes 15 of the foot-plate thereby 100 securing the foot-plate to the wedge blocks and also locking the wedge blocks together in a removable position. If desired, the 105 nails 43 may be driven not only through the wedge blocks 11 but also into the foundation planks 10. 110

It is obvious that I have provided a simple economical arrangement of shores which in use provide a ready means for erecting and supporting concrete forms in an economic manner. 115

When not in use, and if it is desirable to store the shores or transport them, the tubular sections 18 and 19 are allowed to remain one completely telescoping with the 120 other. The foot-plates of each shore may be readily removed from the tubular sections by withdrawing the bolt 17. Also, the head-plates 22 and joist members 25 may be readily taken apart and placed in barrels or other 125 containers for transportation.

I claim as my invention:—

An adjustable shore, comprising a post section, adjustable strip supporting means mounted on said post section, a foot plate 130

for supporting the post section and comprising a relatively flat sheet metal body portion of substantially rectangular configuration and having a pair of its oppositely disposed corners upturned for engagement against the opposite sides of the post, a bolt detachably engaging through said upturned corners of the foot plate and through the post for anchoring the latter to the foot plate, the intermediate corners of the foot plate having apertures therethrough adapted to receive nails and the like, and a base section for engagement beneath said foot plate and comprising a pair of oppositely inclined contacting members adapted for overlapping engagement to support the foot plate and the post section, said base section adapted to be moved into superposed relation to raise the foot plate and the post section, and said 20 nails in the opening of the foot plate adapted to engage said base section for holding the same when adjusted.

In testimony whereof, I have affixed my signature.

25
